FUSE FOR SHELLS.

1,214,586.

Specification of Letters Patent. Patented Feb. 6, 1917.

Application filed July 25, 1913. Serial No. 781,171.

To all whom it may concern:

Be it known that I, HUGO PRAHL, engineer, a subject of the German Emperor, and residing at 14 Moltkestrasse, Dusseldorf, Germany, have invented certain new and useful Improvements in Fuses for Shells; and I do hereby declare the following to be a full, clear, and exact description of the invention, such as will enable others skilled in the art to which it appertains to make and use the same.

This invention relates to fuses for shells of the type which are set by timing caps and wherein automatically operating means, such as clock mechanism, may be used to control firing.

The object of my present invention is to provide means whereby a single firing pin may be controlled by percussion or time mechanism; and a further object is to avoid having any mechanical connection between the firing pin releasing mechanism and the timing cap.

In the accompanying drawings, Figure 1 is a vertical longitudinal sectional view showing the parts in the position they assume before firing. Fig. 2 is a side elevation of the releasing mechanism, taken at right angles to the position shown in Fig. 1. Fig. 3 is a plan view of Fig. 2, showing the releasing mechanism in its locked position. Fig. 4 is also a plan view showing the releasing mechanism unlocked. Fig. 5 is a side elevation with the parts in the position indicated in Fig. 4. Fig. 6 is a plan view showing the means engaging and holding the firing pin. Fig. 7 shows the position of the releasing parts and firing pin before firing. Fig. 8 shows the same parts after firing and before ignition. Figs. 9 and 10 are, respectively, plan views of the parts shown in Figs. 7 and 8. Fig. 11 shows the same parts after being released by clock mechanism. Fig. 12 shows the same parts when released by impact. Figs. 13 and 14 are plan views of the parts shown in Figs. 11 and 12, respectively.

Referring to the drawings, 3 designates the firing pin; 4 the main-spring therefor, 5 and 28 the priming cap which is designed to be exploded by the pin on the recoil of its spring. The pin is normally held retracted by a spiral flange *f* of a rotatable member 23 engaging the underside of the flanged head of the firing pin. The pitch or incli-

nation of the flange *f* is such that the tension of spring 4, acting through the firing pin, constantly tends to rotate member 23 in the direction to effect the release of the firing pin.

The rotatable member 23 is provided with two laterally projecting shoulders *e* and *g* located in different planes and with which a pin 25 of a longitudinally-movable trip bolt 15 is designed to engage. This bolt 15 parallels the firing pin and the rotatable member 23, and is slidably mounted in an outer plate *L* and an inner plate *L'*. At the first impulse, on firing, the bolt 15 slides inwardly or rearwardly, owing to its inertia, causing the pin 25 thereof to disengage shoulder *e* and allow the releasing member 23 to be partially rotated under the influence of spring 4, aided or not by centrifugal force. The rotation of the member 23 is arrested when the more inwardly located shoulder *g* strikes against the end of pin 25, as shown in Figs. 8 and 10. The arrangement of shoulder *g* relatively to pin 25 is such that as soon as bolt 15 is moved, either on its axis or longitudinally thereof, the member 23 will be rotated sufficiently, under the recoil of spring 4, to allow the firing pin to free the flange *f* and be impelled by said spring.

When the device is used as a percussion fuse the release of member 23,—that is, the disengagement of pin 25 from shoulder *g*, (see Fig. 12)—occurs when bolt 15 moves forward on impact. When, however, time mechanism is employed, at a predetermined point bolt 15 will be permitted to rotate on its axis under the pressure of the main-spring, and such rotation being unimpeded the firing pin will be projected forward as soon as it clears flange *f*.

It should be pointed out that the two shoulders *e* and *g* are fixed at certain angles to the longitudinal axis of the releasing bolt 15 in order that a certain resistance shall be interposed to prevent such bolt, or its pin 25, from sliding inwardly on shoulder *e* or outwardly on shoulder *g* under the action of the main-spring, but this resistance must be overcome when the gun is fired or at the impact of the shell.

The trip or releasing bolt 15 carries at its outer end a pin *i* which projects through the outer supporting plate *L* and is equipped with a laterally extending finger 13 with

which releasing mechanism is designed to engage so as to normally prevent the axial rotation of the bolt, and particularly when the pin 25 thereof is in engagement with shoulder *g* after firing but before the predetermined point has been reached for the explosion. The releasing member with which the finger 13 engages is shown in the form of a ring 21 which is formed with an opening 10 to accommodate the projection *c* (Fig. 5) of a locking arm 22 which is rigidly connected to a centrally arranged shaft 29 which is designed to be rotated by automatically operating means, such as clock-mechanism, not shown. The ring 21 is designed to be locked to arm 22 by means of a catch 20 pivoted to said arm at *d* and having a pin or projection *Z* which is designed to enter coincident openings in the ring and arm, 20 as shown in Fig. 3. The catch is normally under the tension of a spring *b* which tends to unlock the catch and release the locking ring 21 so that it may be moved laterally under the pressure exerted thereon by finger 13 of the releasing bolt. The inner wall of setting cap 38 holds the catch in its locking position.

Before the initial impulse, the releasing mechanism is held by pin *i* of bolt 15, such 30 pin lying in the path of arm 22 to prevent the counter-clockwise rotation thereof as shown in Fig. 3. When the arm 22 is so held by pin *i* the catch 20 holds ring 21 to arm 22. This is the normal position of the 35 releasing device before firing. When, however, the releasing bolt 15 moves inwardly or rearwardly, at the first impulse, the pin *i* is withdrawn from the path of arm 22, and the latter, together with the releasing ring 21, is 40 permitted to rotate under the action of the clock-mechanism, and pin 25 is disengaged from shoulder *e*. The bolt 15, after the firing, is prevented from rotating on its axis so long as ring 21 remains locked to arm 22, 45 but when said ring is released by catch 20 it will permit the bolt to rotate under the recoil of spring 4, pin 25 being moved out of the way by shoulder *g*. While the clock-work is rotating arm 22 counter-clockwise, 50 the catch 20 remains in locking position until it arrives opposite a recess *m* formed in the interior of the timing cap 38, whereupon said catch being projected into said recess by the action of its spring *b*, the locking 55 ring 21 will be released, and under the pressure of finger 13 will be moved laterally, permitting the release of the firing pin. The setting is effected by adjusting the timing cap 38 which alters the position of recess 60 *m*, and according to the position of such recess the ignition is accelerated or retarded.

The percussion ignition is always ready for action and requires no special setting.

In order that the clockwork or the time 65 ignition should not explode the shell before

impact, a pin 17 secured to plate L allows the arm 22 and the catch 20 to rotate with the shaft 29 only through a given angle of about 320° or $\frac{4}{5}$ of a circle. The catch 20, which is turned by the clockwork through the shaft 70 29 and arm 22, can only describe an arc of about 320°. If cap 38 is set so that the recess *m* lies in the remaining arc of 40°, the catch 20 cannot enter the recess *m* during the time the clockwork is in action and hence 75 ignition is impossible under such setting. In that event, the release of the member 23 and the firing pin 3 can only occur when the releasing bolt 15 has been caused to slide forward on the impact of the shell (see Fig. 12).

The pin 17 in the normal position of the releasing parts before the gun is fired is directly behind the catch 20 or the arm 22, (Fig. 3) so that it takes up any harmful reaction of the parts 22 and 20 on the shaft 29 and the clockwork when the shell begins to rotate. The parts 22 and 20 would otherwise by reason of their inertia turn the shaft 29 in the opposite direction to that intended, 80 that is, in a clockwise direction. Otherwise a small pinion (not shown) on the shaft 29 engaging with the wheel work of the clock would be bent or broken. The pin 17 therefore serves a double purpose.

According to my present invention the recoil of the main-spring is utilized to free the firing pin from the restraining mechanism; and the same parts may be employed for either time or impact ignition.

I claim as my invention:

1. A shell fuse comprising a spring-imelled firing-pin, means for normally holding said firing-pin retracted and capable of being moved to release said pin by the recoil of the spring thereof, a trip for said holding means comprising a rotatably-movable member, and time mechanism for permitting the rotation of said trip member under the recoil of said spring.

2. A shell fuse comprising a spring-imelled firing-pin, means for normally holding said firing-pin retracted and capable of being moved to release said pin by the recoil of the spring thereof, a trip for said holding means comprising a rotatably-movable member, and time-mechanism for permitting the rotation of said trip-member under the recoil of said spring, said rotatably-movable member preventing action of said time mechanism before firing.

3. A shell fuse comprising a spring-imelled firing-pin, means for normally holding said firing-pin retracted and capable of being moved to release said pin by the recoil of the spring thereof, a trip for said holding means comprising a longitudinally and rotatably-movable bolt, and time-mechanism for permitting the rotation of said bolt, which latter normally prevents action

of said time-mechanism but is automatically moved out of the way upon firing.

4. The combination with a spring-im-pelled firing-pin, of a holding member there-⁶for designed to be moved into releasing po-sition by the tension of the firing-pin spring, said holding member having two shoulders on different planes, a longitudinally-mov-able trip-bolt having a projection for suc-¹⁰cessively engaging said shoulders, said bolt being moved longitudinally on firing to dis-engage its pin from one shoulder and per-mit it to be engaged by the other shoulder, and timing-mechanism for permitting said bolt to rotate to disengage its pin from said second shoulder at a predetermined point after firing.

5. The combination with a spring-im-pelled firing-pin, of a rotatable holding mem-²⁰ber therefor having a spiral flange with which the head of the firing pin engages, said member also having shoulders, a bolt having a pin for successively engaging said shoulders, and means for permitting said bolt to release said holding member.

6. The combination with a firing pin, and means for normally holding the latter re-tracted, of a time-controlled arm, and a longitudinally-movable member normally de-signed to be moved automatically to release said arm and at a predetermined point after firing to release said holding means.

7. The combination with a firing pin, and means for normally holding the latter re-tracted, of a time-controlled arm, a releas-

ing member normally locked to said arm, and a longitudinally-movable and rotatable member normally arresting said arm and holding means and designed on firing to re-lease said arm and at a predetermined point after firing to release said holding means.

8. The combination with a firing pin, and means for normally holding the latter re-tracted, of a time-controlled arm, a releas-ing member normally locked to said arm, a catch for effecting such locking, a bolt for normally arresting said arm and holding means, and means for releasing said catch whereby said bolt may be turned to free said holding member.

9. A shell fuse comprising a casing, a cap having a recess, a firing-pin, means for nor-mally holding the latter retracted, a time-⁵⁵controlled arm, a releasing member, a catch for normally locking said releasing member to said arm, a longitudinally movable and rotatable bolt initially in the path of said arm and designed to be moved from such path on firing, said bolt normally holding said holding means and having a finger for engaging said releasing member which lat-ter when said catch enters said recess and unlocks said releasing member permits said bolt to rotate to free said holding means.

In testimony whereof, I have signed this specification in the presence of two sub-scribing witnesses.
